FRAME FOR A PICTURE OR SIMILAR ARTICLE

Isaac Mershon, New York, N. Y., assignor to Globe Silver
Co., Inc., New York, N. Y., a corporation of New York

Application June 17, 1955, Serial No. 36,568

Term of patent 3½ years

(Cl. D29—20)

Fig. 1

Fig. 1 is a front elevational view of a frame for a picture or similar article showing my new design, the ornamentation shown at parts of the top and left side of the frame being continued for the remainder of said top and left side.

Fig. 2 is an end elevational view thereof, the left half being symmetrically disposed with the right half.

Fig. 3 is a front elevational view on an enlarged scale of the element of ornamentation shown in full lines and repeated in Figs. 1 and 2.

The dominant features of my design reside in the portions shown in full lines.

I claim:

The ornamental design for a frame for a picture or similar article, substantially as shown and described.
